REFRIGERATING SYSTEM

John Kirgan, Easton, Pa., assignor to Ingersoll-Rand Company, Jersey City, N. J., a corporation of New Jersey

Application December 19, 1934, Serial No. 758,183

5 Claims. (Cl. 62—152)

This invention relates to improvements in refrigerating apparatus, and particularly to means for controlling same and avoiding waste of power in the operation thereof.

5 In refrigerating systems of the water-vapor type a liquid refrigerant, such as water, is cooled by vaporizing a part thereof. The vaporization is carried out in a vessel called an evaporator and the vapor is extracted by an evacuator, which 10 simultaneously compresses the vapor and transfers it to a condenser to liquefy it. If the evacuator is a steam jet ejector, both the vapor from the evaporator and the steam used in the operation of the jet are liquefied in the condenser.

15 When the pressure in the condenser is high with respect to that in the evaporator, more steam at higher pressure is needed to remove a given amount of water-vapor from the evaporator; and less steam at lower pressure is required when the 20 difference in the pressures of the condenser and the evaporator is reduced.

An object of the invention is to provide means whereby the consumption of steam is regulated in accordance with pressure conditions in the 25 evaporator and condenser, the pressure in the one being opposed to the pressure in the other and the quantity of steam expended being nicely controlled by the resultant effect thereof, so that waste of power is avoided.

30 Another object of the invention is to facilitate starting of the apparatus without interference from any of the controlling devices in the system.

An additional object of the invention is to provide a member between the condenser and the 35 evaporator subjected to pressure conditions in both so that an element therein will be actuated to regulate the steam for the ejector as working conditions demand; and to enable the connection of the evaporator with said member to be interrupted when the evacuator is not working. This arrangement is particularly useful when a multi-chamber evaporator is employed to enable the system to operate through a wide range of load from full load to part load.

45 A further object of the invention is to provide means whereby the maintenance of conditions as above outlined for the correct operation of the invention is always assured.

50 These and other objects and advantages of the invention are set forth in the following description and the novel features are pointed out in the appended claims. The disclosure, however, is illustrative only and many changes may be made in practice without departing from the principle

of the invention or exceeding the scope and spirit thereof.

On the drawing, Figure 1 shows an outline of one form of the invention, and

Figure 2 is a top view indicating how the invention can be employed when the evaporator contains several chambers; and

Figure 3 is a section of a detail.

On the drawing the numeral 1 indicates an evaporator to which a liquid refrigerant, such as 10 water, is supplied by way of a pipe 2. In the evaporator this pipe is connected to a spray device 3 which delivers the water in the form of several jets. Some of the water is vaporized at once, while the remainder settles on the floor 15 of the evaporator and is withdrawn through a conduit 4 which carries the chilled water to a place where the refrigerating effect is desired. Here the water absorbs heat and can be returned by way of the conduit 2 and be used again. 20

At the top of the evaporator is an evacuator in the form of a steam-jet ejector or thermo-compressor 5 connected to a condenser 6 by way of a discharge casing 7 of the usual design. The ejector 5 is supplied with steam through a pipe 8 and 25 in operation, the steam creates a sufficiently high vacuum in the evaporator 1 to start the evaporation and transfer the vapor from the evaporator to the condenser 6. During operation the necessary vacuum is maintained by the ejector 5. 30

In practice several pounds of steam must be used for every pound of water vapor that is extracted from the evaporator 1. The quantity of steam needed varies according to either the refrigerating load or the temperature of the water 35 supplied to the condenser to cool the latter. In either case the conditions inside the condenser undergo a change and the operation of the steam-jet ejector is affected thereby. When the pressure and temperature within the condenser increase, more steam is necessary, and if these factors rise too high, the operation of the steam-jet ejector may even be stopped. When used for this purpose, the steam-jet ejector has a substantially 40 constant capacity and the quantity of water vapor which it will remove from the evaporator at the low vaporization pressures usually employed and deliver to the condenser is approximately the same, regardless of the amount of steam used, so long as the pressure in the evaporator remains 45 unchanged. Also a steam-jet ejector can not be regulated ordinarily by hand, but must be turned on full at whatever pressure the steam is supplied. To regulate such an ejector therefore requires 50 means which will permit the ejector to discharge 55

just the right quantity of steam and no more, to produce the maximum vapor-removal effect for the pressure and temperature prevailing in the evaporator at a given moment.

- 5 The pressure in the condenser, of course, opposes the admission of steam and vapor, and if this pressure exceeds a predetermined amount, and the ejector ceases to operate no more water will be cooled for the time until the evaporation 10 pressure has greatly increased and the temperature of the chilled water has risen to a considerable extent. To obtain regulation in the manner required by the above conditions, the bottom of the condenser and the top of the evaporator are 15 connected by a U-shaped trap member 9 which contains a float element 10. This element 10 is mounted upon an arm 11 fixed to a pivot 12 that extends outside of the member 9. On its exterior end the pivot 12 bears a rigid arm 13 joined by a 20 link 14 to an arm 15 of a rotary valve 16 in the steam pipe 8. The trap member will fill with the condensate in the condenser and as the pressure in the condenser is always higher than in the evaporator, the liquid in the member 9 will rise 25 to a certain height depending upon the difference between the condenser pressure and the evaporator pressure. Then the float will rise or fall to open or close the valve 16 as the opposed pressures in the condenser and evaporator vary. For 30 example, if the condenser vacuum increases, that is, if the pressure in the condenser diminishes while the pressure in the evaporator remains the same the valve will be closed to some extent because less steam at lower pressure will then be 35 needed to evacuate the evaporator 1. The same result will follow if the vacuum decreases and the pressure increases in the evaporator 1, while the pressure in the condenser remains fixed, because then at higher pressure the amount of vapor created in the evaporator will be smaller. On the other hand, if the absolute pressure in the condenser rises, or in the evaporator it decreases, the valve is opened further to admit more steam at 40 higher pressure to the ejector 5. In other words 45 more steam at higher pressure will be supplied to the ejector when the ratio between the condenser pressure and the evaporator pressure goes up, and the quantity and pressure of the steam will be reduced when this ratio grows less.
- 50 As illustrated in Figure 1, the member 9 is adjacent one end of the evaporator and the condenser and the steam pipe 8 is bent as required at 17 to reach the ejector 5.

55 A by-pass 18 can be arranged around the valve 16 and in this by-pass is a valve 19. The by-pass is used when the apparatus is started so that the supply of steam will be independent of the operation of the float 10. When the apparatus is working well, the by-pass is closed to enable the float 60 10 and valve 16 to function.

65 The member 9 is united to the condenser by the pipe 20 and the drain pipe 21 of the condenser rises above the bottom thereof as shown at 21' to cause enough condensate to collect on the bottom of the condenser to fill the trap 9. At its top the member 9 is joined to the evaporator by the pipe 22.

70 The evaporator may consist of two or more chambers separated by partitions 23 as shown in Figure 2. In this case the steam pipe 8 will be provided with branches 24 beyond the valves 16 and 19 and the chambers are all connected in parallel by separate vents 25 to the trap member 9. Each of these vents 25 will contain a valve 26 75 the stem 27 of which projects to the outside and

tends to be closed by spring 28. Each stem has a head 29 made fast to a diaphragm 30, forming one wall of a casing 31 connected by a pipe 32 to the steam pipe 24 of the associated chamber between the evaporator therefor and the hand valve 33 which controls same. Whenever the steam jet of any chamber is working the pressure of the steam will open the valve 26 in the vent 25 so as to connect that chamber to the member 9, but when any chamber is cut out the spring 28 will close the valve 26 thereof so that this chamber will not communicate with the member 9.

With this construction if the apparatus is operated with all chambers and all ejectors working, and the load drops, one or more of the chambers can be cut out simply by turning the one or more hand valves 33 in the branch steam pipes 24, similar valves 34 in branches 35 of the return or supply pipe 2 and valves (not shown) in branches of the discharge pipe 4 connected to the various chambers. With only the remaining chambers in operation less steam and water vapor are discharged into the condenser, and the water flowing through the condenser becomes cooler and the pressure in the condenser drops. Hence the float element operates to cut down the volume and pressure of the steam which is used in the ejectors of the remaining chambers. The reduced load can thus be carried economically and steam is saved. When the load again increases so that more chambers in the evaporator and more ejectors have to be used again, the vacuum will become less in the condenser and the back pressure against the steam and water vapor will be increased. The float element now opens 35 the steam valve 16 to supply more steam at higher pressure to the ejectors. The float element 10 can be connected to the main valve 16 so as to make this valve responsive to variations in load that are smaller than the variations which take place when one or more chambers are put into operation or cut out, to permit more or less steam at higher or lower pressures to flow through the ejectors of the chambers in the evaporators that are active.

Another function of the device is to control the system if the cooling water supplied to the condenser to liquefy the steam and vapor, changes in temperature. In that case the pressure in the condenser changes and the regulating device 50 works as before.

The valve 10 is thus operated by the float element to vary the amount and pressure of steam delivered to the nozzles of the ejectors according to the pressure difference or pressure ratio between the outlet and inlet pressures of the ejectors. If for any reason the condenser pressure rises while the pressure in the evaporator does not change, more steam at higher pressure will be admitted to the ejectors, and if the condenser pressure falls, less steam at lower pressure will be admitted. If on the other hand the condenser pressure remains substantially fixed and the evaporator pressure rises as when an increase in load takes place, this means a lower pressure ratio and less resistance of the flow into the condenser. The valve element now cuts down the steam as before. If on the other hand while the condenser pressure does not change, the evaporator pressure drops, a rise in the pressure ratio thus occurs and the valve will then open to supply more steam as required. With this construction a great saving in supply of steam in the operation of the apparatus at light 75

loads or with cold condenser water is accomplished and the cost of operation is reduced.

To offset any waste of steam in case of an increased vacuum within the evaporator 1, such as will arise if there is a considerable drop in load, I employ an additional regulating device, preferably of the thermostatic type, to cut down the volume and pressure of the steam. This device comprises a bulb or the like element 36, mounted in the discharge conduit 4, and subject to the chilled water temperature thereof. It is connected by a piece of tubing 37 to suitable mechanism indicated at 38, comprising a movable rod or member 39 joined to the arm of a valve 40 similar to the valve 16, in the steam pipe 8. The valve 16 is between the valve 40 and the evaporator. Consequently, whenever the chilled water temperature drops too much, as when the load falls greatly and a considerable increase in the evaporator vacuum ensues, the larger opening of the valve 16 will be balanced by the partial closing of the valve 40. In the bulb 36 and tube 37 will be an expansible fluid by which the member 39 will be actuated whenever the chilled water temperature sinks to a predetermined figure. A full description of this thermostatic regulator is not necessary, as various kinds known to those skilled in this art will serve the purpose. The thermostatic regulator may also be designed to respond to thermal changes in a medium other than fluid if desired. So long as the system operates above the minimum chilled water temperature selected, the valve 40 will be fully open, and the system will then be controlled by the valve 16 as described.

In Figure 1, the valves 26, 33, 34 and 40 are omitted for the sake of clearness.

I claim:

1. The combination of an evaporator, an evacuator therefor, a condenser to which the evacuator delivers, a member connected to the evaporator and condenser, an element in said

member connected to regulate the power medium for the evacuator, and means for cutting off the connection of said member to the evaporator when the evacuator is not operating.

2. The combination of an evaporator, a jet-operated evacuator therefor, a condenser to which the evacuator delivers, a trap member connected to the condenser and the evaporator, an element in the trap member to regulate the power medium for the evacuator, and means controlled by the pressure of said medium to cut off communication between said member and said evaporator when the evacuator is not operating.

3. The combination of an evaporator, a jet-operated evacuator for same, a condenser to which said evacuator delivers, a trap member connected to the evaporator and condenser and subject to pressure conditions in both, an element in the member connected to control the power medium for the evacuator, means for rendering said element ineffective at starting, and means actuated by the power for the evacuator to cut off communication between the evaporator and said member when the evacuator is not working.

4. A refrigerating system comprising an evaporator chamber, an evacuator therefor, a condenser to which the evacuator delivers, means communicating with the condenser and evaporator and containing an element to control the evacuator and a connection for cutting off said chamber from said means when the chamber is not working.

5. A refrigerating system comprising an evaporator chamber, an evacuator therefor, a condenser to which the evacuator delivers, means communicating with the condenser and evaporator and containing an element to control the evacuator and a connection for cutting off said chamber from said means when the chamber is not working, said connections being dependent on said evacuator.

JOHN KIRGAN.
